US0D1062541S

(12) **United States Design Patent** (10) **Patent No.:** **US D1,062,541 S**
(45) **Date of Patent:** **** Feb. 18, 2025**

(54) **ELECTRIC DIRT BIKE**

(71) Applicant: **Chongqing Yizao Technology Co., Ltd.**, Chongqing (CN)

(72) Inventor: **Wei Guo**, Chongqing (CN)

(73) Assignee: **Chongqing Yizao Technology Co., Ltd.**, Chongqing (CN)

(**) Term: **15 Years**

(21) Appl. No.: **29/903,220**

(22) Filed: **Sep. 21, 2023**

(30) **Foreign Application Priority Data**

Mar. 29, 2023 (CN) 202330160533.6

(51) **LOC (15) Cl.** **12-11**

(57) **CLAIM**

The ornamental design for an electric dirt bike, as shown and described.

DESCRIPTION

FIG. 1 is a left side elevation view of an electric dirt bike showing my new design;

FIG. 2 is a right side elevation view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a bottom, front and right side perspective view thereof; and,

FIG. 8 is a bottom, front and left side perspective view thereof.

The broken lines shown in the drawings depict portions of the electric dirt bike that form no part of the claimed design.

1 Claim, 8 Drawing Sheets
